Att'y.

UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

LIGHT-FIXTURE.

1,267,865.

Specification of Letters Patent.

Patented May 28, 1918.

Application filed December 4, 1916. Serial No. 134,886.

To all whom it may concern:

Be it known that I, CROMWELL A. B. HALVORSON, Jr., a citizen of the United States, residing at Lynn, in the county of Essex, State of Massachusetts, have invented certain new and useful Improvements in Light-Fixtures, of which the following is a specification.

My invention relates to an incandescent lamp fixture and more particularly to the support for the lamp and for the parts associated therewith.

In the operation of incandescent lamps for street lighting and other purposes, it is frequently necessary when operating the lamps either from series or multiple circuits, to use a transformer in connection with the lamp in order that the latter may be operated at its rated voltage. My invention relates particularly to a fixture of this type which is compact, cheap and of few parts.

My invention will best be understood by reference to the accompanying drawing, in which Figure 1 is a perspective view partially broken away, disclosing a lighting unit embodying my invention; Fig. 2 is a plan view of the top of the lamp support and the insulating base carried thereby; Fig. 3 is a section taken on Fig. 2; and Fig. 4 discloses my invention embodied in a lamp of a different type.

Referring now to the drawings, 10 is a base support which comprises an upper removable section 11 formed at its lower edge with a flange 11^a which engages a corresponding rabbet in the upper end of the stationary part of the support. The upper end of the section 11 is provided with a flange 12 within which a suitable globe may be mounted. A canopy 14 may be carried on the top of the globe. A high voltage insulating base 15 of suitable material, such as porcelain, is mounted in the top of the removable section 11 of the support, and constitutes a supporting base both for an incandescent lamp 20 and for a transformer 21 associated therewith. The insulating base 15 is preferably provided with a ledge 16 formed with notches 17 which engage one or more lugs 18 or projections 18 (one of which is shown in Fig. 3) formed on the inner side of the casing 11, which lugs hold the insulating base in position. On one side of the insulating base is mounted a lamp socket 19 in which the incandescent lamp 20 is received. When

the lamp is carried by a post or standard, as in Fig. 1, the socket is mounted on the upper side of the insulating base. On the lower side of the base is secured the transformer 21 which in practice will usually be an autotransformer. This comprises a core 22 secured to the insulating base by brackets or angle irons 23, and coils 24 from which suitable conductors 25 are connected to the lamp socket.

It will be apparent that the insulating base 15 serves as a high voltage insulator both for the incandescent lamp and for the transformer which is associated therewith, and that the whole fixture is simple and compact, and may readily be removed as a unit from its support. It will also be apparent that the removable portion 11 constitutes the support for the fixture and at the same time serves as a housing for the transformer, and is amply spaced therefrom in order thoroughly to insulate the transformer from the support.

In Fig. 4 I have shown my invention embodied in a suspended type of lamp, in which the same parts are present, but the lamp is suspended beneath the insulating base and the transformer mounted on the upper side thereof.

In accordance with the provisions of the patent statutes, I have described the principle of operation of my invention, together with the apparatus which I now consider to represent the best embodiment thereof, but I desire to have it understood that the apparatus shown is only illustrative, and that the invention can be carried out by other means.

What I claim as new and desire to secure by Letters Patent of the United States, is:

1. In combination, a support, an insulating base mounted thereon, an incandescent lamp socket mounted on one side of said base, and a transformer mounted on the opposite side thereof and electrically connected to said socket.

2. A lighting fixture comprising an insulating base, an incandescent lamp socket mounted on one side thereof, a transformer mounted on the opposite side thereof and electrically connected to the lamp socket, and a casing in which the insulating base is mounted and which serves as a housing for the transformer.

3. A lighting fixture comprising a casing

having a globe mounted thereon, an insulating base supported by said casing and having on one side a transformer housed within said casing and on the opposite side a lamp socket extending within the globe.

4. A lighting fixture comprising an insulating base, a lamp socket mounted on one side thereof and a transformer mounted on

the opposite side thereof and a casing surrounding the transformer and provided with 10 one or more projections on which the insulating base is mounted.

In witness whereof I have hereunto set my hand this 1st day of December, 1916.

CROMWELL A. B. HALVORSON, JR.
